UNITED STATES PATENT OFFICE.

LOUIS SANDERS, OF NEW YORK, N. Y.

BELT-BUCKLE.

SPECIFICATION forming part of Letters Patent No. 624,872, dated May 9, 1899.

Application filed December 21, 1898. Serial No. 699,922. (No model.)

To all whom it may concern:

Be it known that I, LOUIS SANDERS, of the city of New York, borough of Brooklyn, in the county of Kings and State of New York, have 5 invented a new and useful Improvement in Belt-Buckles, of which the following is a full, clear, and exact description.

The object of my invention is to provide a buckle especially adapted for military belts 10 and which is arranged to be opened and closed by vertical movement of its members.

Another object of the invention is to construct a buckle of the type above described that will be simple, durable, and economic 15 and that will not be liable to separate or work loose under the movements of the body necessary during military duty.

The invention consists in the novel construction and combination of the several 20 parts, as will be hereinafter fully set forth, and pointed out in the claims.

Reference is to be had to the accompanying drawings, forming a part of this specification, in which similar characters of reference indicate 25 corresponding parts in all the figures.

Figure 1 is a front elevation of the improved buckle and a portion of a belt attached thereto. Fig. 2 is a rear elevation of the buckle closed. Fig. 3 is a rear elevation of one 30 member of the buckle, and Fig. 4 is a rear elevation of the mating member of the buckle. Fig. 5 is a longitudinal vertical section taken practically on the line 5-5 of Fig. 2; and Fig. 6 is a front elevation of the member of the 35 buckle illustrated in Fig. 4, but reversed end for end from the position shown in Fig. 4.

A represents one member of the improved buckle, B the mating member, and C a portion 40 of a belt attached to the buckle. The front of the members of the buckle may be given any desired contour or configuration. The rear of each member, however, is provided at its outer side at top and bottom with two guides 10 and 11, the guides 10 being the 45 outer guides, and the said outer guides project rearwardly beyond the plane of the rear faces of the inner guides, as shown in Fig. 5. The upper guides of the buckle members extend downwardly, while the bottom guides 50 extend upwardly. In attaching the ends of the belt C to the members of the buckle each end is first passed inward between the inner

guides 11 and the inner face of the respective member of the buckle and is then returned upon itself and carried outward, passing between the guides 11 and the outer guides 10. Upon the inner face of the member B of the buckle, near the inner edge of said member, studs 12 are located. The studs are preferably two in number, being located one at each 55 side of the center, and between the studs 12 a rearwardly-extending teat 13 is formed, said teat being usually produced by striking up the material of the member B from the front.

The mating member A of the buckle is provided with a lip 14, laterally projected from its inner edge, and the said lip where it connects with the inner edge of the member A is carried rearwardly to extend beyond the plane of the inner face of the member, as shown in 65 Fig. 4. Bayonet-slots 15 are made in the lip 14, corresponding in number to the number of studs 12 employed in constructing the buckle. The entrance-sections a of the bayonet-slots are sufficiently wide to freely admit 70 the studs 12, while the receiving-section a' of each bayonet-slot where it connects with the entrance-section is of less width than the width of said entrance-section; but the receiving-section a' of each of the said bayonet-slots is provided with an enlargement a^2 at 75 its inner extremity, so that when the members of the buckle are brought together and the studs 12 are passed from the entrance-sections of the bayonet-slots 15 into the receiving-sections of said slots the studs will 80 meet with resistance; but when the studs enter the enlarged portions a^2 of said bayonet-slots the studs will have sufficient play to 85 enable the buckle to be comfortably worn, as 90 the play of the studs will be sufficient to provide for any movement necessary on the part of the wearer.

A depression 16 is made in the lip 14 between the bayonet-slots, being adapted when 95 the members of the buckle are closed together to receive the teat 13 of the member B of the buckle, and adjacent to the depression 16 a transverse groove 17 is made in the lip 14 of the member A, the said groove being adapted 100 to receive the teat 13 of the member B when the two members A and B are brought together. When the studs 12 are introduced into the entrance-sections a of the bayonet-

slots 15, the two members of the buckle are firmly locked together by carrying the member B upward after it is received by the member A until the studs 12 have been received 5 in the enlarged portions a^2 of the bayonet-slots 15 and the teat 13 of the member B has been sprung into the recess 16 in the lip of the member A, as illustrated in Fig. 5.

A buckle constructed in the manner herein 10 shown and described is not only simple, durable, and economic, but the members of said buckle will be firmly held together and cannot be separated under any movement of the body of the wearer necessary to martial exercise. In fact, it is absolutely necessary to 15 impart vertical movement to the members of the buckle before the said members can be disconnected from each other.

It will be observed that when the members 20 of the buckle are to be brought together the groove 17 serves as a guide for the member A and that the teat that enters the groove 17 must be sprung out therefrom into its receiving-recess 16 in order to effect a perfect locking engagement between the two buckle members.

In the construction of the buckle false stud-heads 12^a are preferably formed upon the front of the member A, and a mock depression 13^a 25 is made likewise in the front face of the said member. The mock stud-heads are in transverse alinement with the rear stud-heads 12 and the mock depression 13^a is in transverse alinement with the depression made in the member B to produce the teat 13, as shown in Fig. 1.

Having thus described my invention, I claim as new and desire to secure by Letters Patent—

40 1. A buckle, comprising two members, one of said members being provided with studs upon its inner face, and the other member being provided with a lip adapted to extend across the inner face of the mating member, 45 the lip being provided with bayonet-slots adapted to receive said studs, the horizontal

or entrance section of said slots opening at the edge of the lip, a portion of the bayonet-slots being of less width than the entrance-sections of said slots, the said members of 50 the buckle being provided with interlocking means, located respectively between the bayonet-slots of one member and the studs of the other member, as and for the purpose specified.

55 2. In a belt-buckle, the combination, with a member provided with studs upon its inner face and a teat between the studs, of a mating member provided with a lip adapted to extend over the inner face of the member provided with the studs, said lip being provided with bayonet-slots, portions of the bayonet-slots being narrower than the entrance-sections of said slots, the closed ends of the bayonet-slots having a greater width than the diameter of the studs adapted to enter said slots, the said lip being provided between the bayonet-slots with a transverse groove in its inner face and also with a depression adjacent to the groove, the said groove being adapted as 70 a guide for the said teat and the depression as a locking-seat for the teat, as set forth.

3. A buckle, comprising two members, each provided at the outer side of its rear face at top and bottom with two guides, studs upon 75 the inner face of one of said members near the inner edge thereof, a lip projected laterally from the inner edge of the other member, the said lip being carried rearwardly to extend beyond the plane of the inner face of 80 said member the said lip being adapted to extend across the inner face of the mating member and provided with bayonet-slots opening at the inner edge of the lip, and adapted to receive said studs, a portion of said slots being of less width than the entrance-sections of said slots, as and for the purpose specified.

85 LOUIS SANDERS.
